UNITED STATES PATENT OFFICE.

JEAN BAPTISTE IMMERS, OF BRUSSELS, BELGIUM.

AEROPLANE.

Application filed December 27, 1924. Serial No. 758,447.

To all whom it may concern:

Be it known that I, JEAN BAPTISTE IMMERS, a subject of the King of the Belgians, residing at Brussels, Belgium, 33 Rue des Osiers, have invented a new and useful Improvement in Aeroplanes, of which the following is a specification.

The present invention relates to an improvement in aeroplanes and is more particularly characterized by the provision of a pair of mutually inter-engaging rotary sustaining elements each consisting of a plurality of longitudinal plane surfaces arranged radially at equal angular intervals in cross section and mounted on a rotary shaft, the two shafts lying in the same horizontal plane and extending substantially parallel to the longitudinal axis of the fuselage and symmetrically on either side respectively of the vertical plane of the said longitudinal axis. If desired, two pairs of the aforesaid rotary sustaining elements may be provided, in which case the two pairs of shafts have their two central longitudinal axes extending symmetrically on either side respectively of the longitudinal axis of the fuselage. An operative connection of any suitable type is provided between the aeroplane-engine and the aforesaid shaft for rotating the two shafts of each pair of rotary sustaining elements in opposed directions.

In order that the invention may be readily understood, it will now be further described with reference to the accompanying purely diagrammatic drawing, wherein:

Fig. 1 is a perspective view of a pair of rotary sustaining elements of the type referred to above;

Fig. 2 is a perspective view of an aeroplane having one form of the invention applied thereto;

Fig. 3 is a perspective view of another type of aeroplane according to the invention;

Fig. 4 is a perspective view showing an aeroplane according to the invention, wherein the usual transversely extending wings are omitted; and

Fig. 5 is a perspective view of a modified type of rotary sustaining elements.

Referring to Fig. 1 of the drawing, it will be seen that the rotary sustaining elements which are, according to the invention, pro-

vided in pairs, each consist of a plurality of longitudinal plane surfaces 1 which are

arranged radially at equal angular intervals in cross section and are mounted on a rotary shaft 2. The two shafts 2 are parallel and lie in the same horizontal plane, and the relative arrangement of the plane surfaces 1 is such that when the shafts 2 are rotated in opposed directions a surface 1 belonging to one of the rotary elements and a surface 1 belonging to the other will pass alternately in the space between the two shafts. The latter instead of being parallel, may be slightly divergent towards the rear of the aeroplane, and the plane surfaces 1, instead of being straight as shown, may be slightly curved or have a very elongated helicoidal shape. The said shafts 2, which extend substantially parallel to the longitudinal axis of the aeroplane, are driven by means of two sprockets 3 mounted on one of the ends of said shafts 2 of two endless chains 4 passing over driving sprockets 5 which are driven by the aeroplane-engine.

Referring to Fig. 2, in which 6 indicates the wings, and 7 the fuselage of an aeroplane, the latter is fitted with a single pair of rotary sustaining elements 1 of which the two shafts 2 are situated in a common horizontal plane above the level of the wings 6, and extend symmetrically on either side respectively of the vertical plane of the longitudinal axis of the fuselage 7. The said shafts 2 are rotatably carried by suitable supports 8.

Fig. 3 shows an embodiment wherein two pairs of rotary sustaining elements 1 are provided symmetrically on either side respectively of the vertical plane of the longitudinal axis of the fuselage 7, the shafts of the said rotary elements 1 lying substantially in the same horizontal plane as that of the wings 6 of the aeroplane.

In the embodiment illustrated by Fig. 4, a single pair of rotary sustaining elements 1 is provided above the fuselage 7, but the said elements are made of such a size that the usual wings may be dispensed with.

As illustrated by Fig. 5, each of the individual plane surfaces of the type of rotary sustaining elements shown in Fig. 1 may be replaced by a longitudinal series or row of paddle-like surfaces 1'. The plane surfaces of the rotary sustaining elements are preferably made of fabric but may be made of any other suitable material.

It has been found experimentally that when the two shafts of each pair of rotary

sustaining elements are caused to rotate in opposed directions diverging upwardly and outwardly from the median vertical plane passing between the two said shafts the air 5 is chased downwardly under the rotary elements by the intermeshing plane surfaces of the two elements constituting each pair, while a suction is provided immediately above the said elements, so that the rotation 10 of the rotary elements has an action somewhat similar to that of the flapping wings of the birds, whereby considerable assistance is afforded to the aeroplane when rising.

It should be understood that the plane surfaces or series of plane surfaces constituting each of the rotary elements referred to above need not be limited to four as illustrated in the accompanying drawing, but may be in any desired number.

20 I claim:

1. In an aeroplane, the combination with a fuselage, an aeroplane engine, and wings extending substantially transversely in relation to the longitudinal axis of the fuselage, 25 of a pair of mutually interengaging rotary sustaining elements each consisting of a plurality of longitudinal plane surfaces arranged radially at equal angular intervals in cross-section and mounted on a rotary shaft, the two shafts lying in the same horizontal plane and extending substantially parallel to the longitudinal axis of the fuselage and 30 symmetrically on either side respectively of the vertical plane of the said longitudinal axis; and of means, forming an operative connection between the said shafts and the aeroplane engine, for rotating the said two shafts in opposed directions; substantially as described.

40 2. In an aeroplane, the combination with a fuselage, an aeroplane engine, and wings extending substantially transversely in relation to the longitudinal axis of the fuselage,

of two pairs of mutually intermeshing 45 rotary sustaining elements each consisting of a plurality of longitudinal plane surfaces arranged radially at equal angular intervals in cross-section and mounted on a rotary shaft, the two pairs of shafts lying in the same horizontal plane and having their two 50 central longitudinal axes extending parallel to the longitudinal axis of the fuselage and symmetrically on either side respectively of the vertical plane of the said longitudinal axis; and of means, forming an operative connection between the said shafts and the aeroplane engine, for rotating the said two shafts of each pair in opposed directions; 55 substantially as described.

3. In an aeroplane, the combination with 60 a fuselage, an aeroplane engine, and wings extending substantially transversely in relation to the longitudinal axis of the fuselage, of a pair of mutually interengaging rotary sustaining elements each consisting of a 65 plurality of longitudinal series of paddle-like plane surfaces arranged radially at equal angular intervals in cross-section and mounted on a rotary shaft, the two shafts lying in the same horizontal plane and extending substantially parallel to the longitudinal axis of the fuselage and symmetrically on either side respectively of the vertical plane of the said longitudinal axis; and of means, forming an operative connection 70 between the said shafts and the aeroplane engine, for rotating the said two shafts in opposed directions; substantially as described.

In testimony whereof I signed hereunto 80 my name in the presence of two subscribing witnesses.

JEAN BAPTISTE IMMERS.
